UNITED STATES PATENT OFFICE.

EDWARD A. FRANKLIN, OF BRENHAM, TEXAS.

IMPROVEMENT IN NAIL-EXTRACTORS.

Specification forming part of Letters Patent No. 126,686, dated May 14, 1872.

Specification describing a new and Improved Nail and Tack Extractor, invented by EDWARD A. FRANKLIN, of Brenham, in the county of Washington and State of Texas.

Figures 1 and 2 represent side views of my improved nail and tack extractor, showing the parts in different positions.

Similar letters of reference indicate corresponding parts.

The object of this invention is to produce an instrument for readily extracting nails, tacks, brads, &c., from the matter into which they have been forced, which instrument will increase its effectiveness in equal ratio with the resistance offered by the object under operation. The invention consists in a novel arrangement of levers and claws, as hereinafter more fully described.

A in the drawing represents the main lever of the device, having a claw, *a*, at one end and a handle, *b*, at the other end, and a projecting ear, *c*, a short distance behind the claw. B is a lever, pivoted to A at *d*, between the ear *c* and the point of the claw *a*. The upper end of the lever B connects by a pivot, *e*, with the rear end of a lever, D, while its lower end has a pad or rough edge, *f*, to rest on the floor.

The lever D has its rear end pivoted at *e* to the lever B, and its middle at *g* to the front end of another lever, E, whose rear end is pivoted to the upper end of the ear *c*. The front end of the lever D forms the second claw *h*.

When the device is to be used the claw *a* is placed against the nail to be extracted, the pad *f* resting on the floor, as in Fig. 1. The handle *b* is then swung down, causing the claw *a* to be crowded against the nail and the lever B to be swung nearer vertical, which will so swing the lever D as to bring the claw *h* against the other side of the nail, as in Fig. 2. The further motion in the same direction of the lever A will elevate the claw *a*, and still more crowd the claw *h* against the nail, causing the certain extraction of the latter.

Having thus described my invention, I claim as new and desire to secure by Letters Patent—

The nail-extractor, consisting of the levers A, B, D, and E, all arranged substantially as herein shown and described.

EDWARD A. FRANKLIN. [L. S.]
